CONTROL DEVICE FOR GASEOUS
FUEL BURNERS

Harold W. Rice, Los Angeles, Calif., assignor to
Robertshaw-Fulton Controls Company, a cor-
poration of Delaware

Application May 18, 1946, Serial No. 670,756

10 Claims. (Cl. 137—139)

1

This invention relates to control devices for gaseous fuel burners and, more particularly, to combined safety and timing controls.

Domestic gas cooking ranges may have the main or oven burner controlled by automatic timing means such as an electric clock timer so that the flow of fuel is automatically shut off at the end of a cooking period. The shut-off element may also be under the control of a safety device which operates independently of the timing device to prevent the flow of fuel to the main burner whenever an associated pilot burner is not burning. The safety device is usually of the thermomagnetic type and requires resetting to a fully operative position each time the pilot burner is lighted. It becomes important, therefore, to prevent the flow of fuel to the main burner during the resetting operation even if the clock timer is then in position where the shut-off element would ordinarily be ineffective to prevent the flow of fuel.

An object of this invention is to prevent the flow of fuel to a main burner during resetting or whenever a safety device is not fully operative.

Another object of the invention is to control the flow of fuel to the main burner by a single shut-off element which is responsive to both a timing means and a thermomagnetic safety device.

Another object of the invention is to render the shut-off element normally responsive to the safety device even if the timing means is no longer operative.

Another object of the invention is to afford easy access to those parts of the control requiring manual operation.

Another object of the invention is to visually indicate the operative or inoperative condition of the safety device.

Other objects and advantages will become apparent from the following description taken in connection with the accompanying drawings wherein:

Fig. 1 is a front elevation partly in longitudinal section of the combined safety and timing control and showing the timing means in broken lines;

Fig. 2 is a section taken on the line II—II of Fig. 1;

Fig. 3 is a top plan view with the cover broken away to show the inside structure of the combined safety and timing control;

Fig. 4 is a section taken on the line IV—IV of Fig. 3; and

Fig. 5 is a section taken on the line V—V of Fig. 1.

Referring to the drawings, the control device comprises generally a control means 10, a positioning means 12 and a holding means 14, all of which will be described more fully herein-

after. In the arrangement shown, the axes of the control means 10, the holding means 14 and the positioning means 12 are substantially parallel and the control and holding means are arranged in substantially the same horizontal plane with the positioning means 12 in intermediate overlying relationship. As indicated in Fig. 3, the control device as a unit is conveniently secured by any suitable means (not shown) upon the back-guard of a domestic gas range where it normally will be hidden from sight of the range user. As indicated schematically in Fig. 1, the gas range is supplied with fuel from a main fuel pipe 18 to which a conduit 20 is connected for supplying fuel to a pilot burner 22. The pilot burner 22 is located in lighting proximity to a main burner 24 which is connected to the control means 10 by a fuel pipe 26.

The control means 10 comprises a generally rectangular hollow body 28 having an inlet opening 30 and an outlet opening 32 in the underside thereof and being suitably threaded or otherwise formed for connection with the fuel pipes 18 and 26, respectively. A partition 34 is formed integrally within the body 28 and serves to separate the inlet opening 30 from the outlet opening 32. Passage of fuel between these openings is provided for by the provision of an opening 36 extending through the partition 34 axially of the valve body 28 and being provided on one side of its peripheral wall with a valve seat 38. A valve member 40 is cooperable with the valve seat 38 to control flow of fluid through the opening 36 and is normally biased to closed position by a coil spring 42 operative between the valve member 40 and a closure cap 44 threadedly secured in an opening 45 formed in the body 28 between the inlet and outlet openings.

A valve stem 46 is secured to the valve member 40 on the side opposite the coil spring 42 and extends through the opening 36 into slidably engagement with a stem bushing 48 which is threadedly secured to the body 28 opposite the cap 44. The bushing 48 may be assembled in the body 28 by insertion through the threaded opening 45 and the valve seat opening 36 before the cap 44 is positioned. The valve stem 46 extends through the bushing 48 into abutting engagement with a sealing diaphragm 50 which is similarly engaged on the opposite side by an operating stem 52 axially aligned with the valve stem 46 and extending exteriorly of the body 28. It is apparent that pressure applied to the projecting end of the operating stem 52 will be transmitted to the valve stem 46 through the diaphragm 50 and will serve to overcome the bias of spring 42 to disengage the valve member 40 from its seat 38.

The holding means 14 is of the thermomagnetic type and comprises a magnet housing 54 within

which a horseshoe magnet 56 is rigidly mounted. An armature member 58 is adapted to be moved into attracted position with the pole faces of the magnet 56 against the bias of a coil spring 60. The coil spring 60 is operative between an outer end face of the magnet housing 54 and an end face of an extension 62 of an armature stem 64 which projects from the housing 54. The armature stem extension 62 is rigidly secured to the armature stem 64 and is provided with an annular groove 66 and a reduced axial portion 68 which portion is adapted for slidable engagement with an axial opening 70 formed in one end of a thrust button 72. It may be noted here that the bore 70 is formed somewhat deeper than the entire length of the reduced portion 68 for a purpose to be described hereinafter.

Both the control device 10 and the holding means 14 are mounted upon the underside of a rectangular platform 74 which may be utilized to secure the control device as a unit to the back-guard of the range. In the case of the control means 10 the securing means takes the form of a pair of screws 76 each provided with a collar 78 which serves to space the control body 28 from the platform 74. In the case of the holding means 14 an angular frame 80 (shown more clearly in Fig. 4) is employed and is provided with a pair of ears 82 at one end with which a pair of screws 84 cooperate to secure the frame 80 to the underside of the platform 74. The frame 80 has a portion extending substantially normal to that portion having the ears 82 and a base portion 86 extending substantially parallel to the latter portion. The magnet housing 54 is mounted on the base portion 86 and is secured thereto by means of a nut 88 which engages with a threaded extension of the magnet housing 54.

Preferably, a casing 90 of sheet material encloses the holding means 14 and extends between the control body 28 and the platform 74. Hence, the casing 90 may conveniently be supported at one end between the collars 78 associated with the control body 28 and at the other end by a lock-nut 92 which engages the threaded extension of the magnet housing 54 on the opposite side of the casing 90 to the nut 88.

The holding means 14 is responsive to a controlling condition and, in this embodiment, is responsive to the presence or absence of a flame at the pilot burner 22. Thus, a winding 94 is provided for the magnet 56 and is adapted to be energized by current generated by a thermocouple 96. As shown schematically in Fig. 1, the thermocouple 96 is electrically connected at one end with the winding 94 and has its hot junction exposed to the flame of the pilot burner 22. The current flow so generated is sufficient to retain the armature 58 in attracted position relative to the pole faces of the magnet 56 but is insufficient to actuate the armature 58 to this position. Consequently, manual resetting means, now to be described, are employed to place the armature 58 in attracted position and render the holding means effective.

The resetting means, as shown most clearly in Fig. 4, comprises a push-button 98 which is secured on one end of a slide bar 100 which extends through aligned apertures 102 formed in upturned flanges 104 of a support plate 106. The support plate 106 is secured to the platform 74 by screws 108. The support plate 106 and the platform 74 are suitably apertured for the reception of a head portion 110 formed on the thrust button 72 and defining a collar 112 thereon which

abuts against the underside of the platform 74. Manual pressure applied to the push-button 98 is transmitted to the thrust button 72 by a bell-crank lever 114 having one leg projecting through an aperture 116 in the slide bar 100 and another leg projecting through a slot 117 in the adjacent upturned flange 104 and terminating in a rounded end 118 for operative engagement with the head 110 of the thrust button 72. The lever 114 is adapted for pivotal movement on the support plate 106 by the provision of oppositely disposed lugs 120 formed at the junction of the two legs of the lever 114 and loosely mounted within oppositely disposed arcuate bearing portions 122 formed on the adjacent end of the support plate 106.

The positioning means 12 takes the form of a push rod 124 conveniently formed in three parts for ease of assembly. One part comprises a headed stem 126 having an axial aperture therein suitably threaded for engagement by a second headed stem 128 for securing these parts rigidly together. The two stems 126 and 128 are mounted for slidable movement within a bushing 130 which is secured by welding or other suitable method in an aperture in the platform 74 positioned intermediate the control means 10 and the holding means 14. The headed stem 128 projects on the underside of the platform 74, whereas the headed stem 126 projects on the opposite side thereof and is spaced from the end face of the bushing 130 to permit reciprocable movement of the push rod 124. As indicated in broken lines in Fig. 1 of the drawings, the push rod 124 is adapted for operative engagement with the operating stem (not shown) of an electric clock 132 which is shown positioned on the platform 74 surmounting the control means 10 and the holding means 14. The clock 132 forms a timing or other condition controlling means for governing the length of the cooking operation, as will be hereinafter apparent and may be detachably secured to the platform 74 by engagement with snap buttons 134 yieldably mounted on the platform 74.

This invention is more particularly directed toward means for operating the valve member 40 to control flow of fuel to the main burner 24 for the period set by the clock, or other condition controlling means, and for causing the valve to close to shut off the fuel supply to the main burner 24 in the event that the pilot burner 22 becomes extinguished. To this end, a lever device designated generally at 136 is provided for transmitting movement of the push rod 124 to the valve member 40 and also for transmitting movement of the manual push button 98 to the holding means 14.

The lever device 136 takes the form of a pair of lever arms 138 and 140 positioned for pivotal movement within the casing 90. The lever arm 138 is pivoted intermediate its ends on the lever arm 140 and extends from the axis of the control means 10 to beyond the axis of the holding means 14. Thus, a pair of depending ears 142 are provided on the lever arm 138 and bear against the sides of the lever arm 140 which is of channel-shaped form. A pin 144 extends through the ears 142 and the sides of the lever arm 140 to form the pivot point or fulcrum of the lever arm 138. The motion of the lever arm 138 is transmitted to the stem 52, which projects from the control body 28, by means of an adjusting screw 146 which extends perpendicularly from the lever arm 138 into engagement with the end of the stem 52.

The opposite end of the lever arm 138 beyond

the holding means 14 is engaged by a coil spring 148 which is operative between the lever arm 138 and a stationary angular arm 150 projecting from the frame 86. The coil spring 148 tends to rotate the lever arm 138 in a counter-clockwise direction on the pivot 144 and overcomes the bias of the coil spring 42 while maintaining engagement between the lever arm 138 and the headed stem 128 of the push rod 124 of the timing mechanism. The lever arm 138 is further provided with an aperture through which the thrust button 72 extends and the sides of the lever arm adjacent the aperture are suitably crimped to provide a raised bearing surface 152 for engagement with the shoulder 112 on the thrust button 72.

As previously stated, the other lever arm 140 is of channel form and is mounted for pivotal movement on a pin 155 carried by a relatively stationary support 154 through which it extends substantially parallel with the pivot pin 144 for the lever 138. The support 154 depends from the underside of the platform 74 to which it is secured by a screw 156. The lever arm 140 is provided with an extension 158 beyond the channel-shaped portion which terminates in a notched end for operative engagement with the recessed portion 66 of the magnet stem extension 62. Thus, upon reciprocation of the stem extension 62 the lever arm 140 will be rotated on its pivot 155.

In order that visual indication of the condition of the thermomagnetic means may be provided for the operator, suitable indicating means are provided. Thus, the lever arm 140 is provided with an upturned projecting portion 160 which extends from adjacent the pivot 155 through an aperture in the platform 74 and is engaged by one end of a link member 162. The opposite end of the link member 162 is engaged with an indicator arm 164 pivotally mounted at one end on a screw 166 projecting from the platform 74 and having its opposite end provided with an arcuate plate 168 carrying the indicia "on" and "off." A pair of stop pins 170 project from the platform 74 and are spaced one from the other on either side of the indicator arm 164 to limit pivotal movement thereof in two positions for displaying either of the indicia through a window 172 formed in the front casing of the clock 132.

A second casing 174 of sheet material is provided to enclose the indicating mechanism and the resetting means. This casing 174 has crimped projecting ends 175 which extend through suitable apertures in the platform 74 and serve as resilient locking means to detachably retain the casing in position. An aperture 176 is provided in the top of the casing 174 through which the push-rod 124 may project and, similarly, apertures 177 and 179 are provided in the front therethrough through which the push-button 98 may project and the indicia on the arcuate plate 168 may be viewed through the window 172 respectively. The front casing of the clock 132 is additionally apertured to permit the push-button 98 to project therethrough as indicated in Fig. 3.

In the operation of the device, the condition controlling means such as the electric clock 132 may terminate the cooking period by closing the valve 40 which is shown in the open position with both burners 22 and 24 in operation. In this valve closing operation, the push-rod 124 is forced downwardly by the clock actuator (not shown) so that the threaded stem 128 which is engaged with the lever arm 138 causes this lever arm to pivot about the pin 144. Thus, a clockwise move-

ment of the lever arm 138, as viewed in Fig. 1, occurs causing the adjusting screw 146 to be raised allowing the valve spring 42 to close the valve 40. On the other hand, when the clock 6 operates to open the valve 40, the downward force on the push-rod 124 is removed. The coil spring 148 then rotates the lever arm 138 counter-clockwise and causes movement of the valve 40 from its seat 38 against the bias of the valve spring 42.

10 In the event that the flame from the pilot burner 22 is extinguished, then the thermocouple 96 ceases to generate sufficient current to maintain the armature 58 in attracted position relative to the pole faces of the magnet 56. The stem extension 62 is moved upwardly as viewed in Fig. 1, by the bias of the coil spring 60 so that the shoulder thereon engages the underside of the thrust button 72. The extension 158 of the lever arm 140, which engages the recessed portion 66, 15 is thus rotated counterclockwise on its pivot 155 causing the other pivot pin 144 to be raised. As the lever arm 138 is attached to the pin 144 it is caused to rotate about the headed stem 128 as a fulcrum and to lift the adjusting screw 146 whereby 20 upon the valve 40 is closed under bias of the spring 42. It is apparent, however, that if the push-rod 124 is being forced to its downward position by the clock actuator at the time that the magnet 56 releases the armature 58, then the 25 valve 40 is initially closed. The lever arm 140 nevertheless rotates as described and causes the lever arm 138 to move still farther. Thus, if the clock actuator releases pressure on the push-rod 124 the valve 40 cannot open.

30 35 During the period that the pilot flame is burning and the holding means 14 is effective, indicia "On" appears in the window 172. This is due to the lever arm 140 being held downwardly and causing the upturned portion 160 thereof to operate the indicator arm 164 to the right, as viewed in Figs. 1 and 3, thus positioning the plate 168 against the right-hand stop pin 170. However, when the pilot flame is extinguished and the lever arm extension 158 moves counter-clockwise 40 as described, then the upturned portion 160 of lever arm 140 moves to the left and reverses the position of the plate 168 through the linkage described. The indicia "off" then appears in the window indicating to the operator that the pilot 45 burner needs relighting. The indicia "on" does not, of course, change during a normal cooking operation when the clock actuator operates the lever arm 138 only and causes opening and closing of the valve 40 to control the main burner 24. 50 55 It is only when the magnet 56 releases and operates lever arm 140 that the indicia is changed from "on" to "off" indicating that the holding means is no longer effective.

60 65 After the described safety operation due to extinguishment of the pilot burner 22, the device must be reset before another cooking operation can be conducted. The pilot burner is first relighted and, after a short waiting period, the thermocouple heats sufficiently to generate current for holding the armature 58 in attracted position. The push-button 98 is then manually operated to cause the bell crank 114 to force the thrust button 72 downwardly as viewed in Fig. 1, or to the left as viewed in Fig. 4. Since the extension stem 62 is initially in abutting relation with the end face of the thrust button 72, then the lever arm extension 158 is moved clockwise due to its engagement with the recessed portion 66. After a relatively short movement in this 70 75 direction, the collar 112 on the thrust button

contacts the bearing surface 152 on the lever arm 138, provided that the push rod 124 is in its retracted position and is not being forced downwardly by the clock actuator. In the retracted push rod position, the lever arm 138 is moved in a clockwise direction causing both the coil springs 148 and 60 to be compressed. During this resetting operation the other lever arm 140 is also rotated clockwise so that both lever arms 138 and 140 are rotated about the pivot pin 155. The armature is thus reset in attracted position relative to the pole faces of the magnet 56 and is retained in such position until the pilot burner 22 is again extinguished. It will be apparent from the previously described action that the indicia "on" appears in the window 172 when the resetting operation is completed.

It should be noted that the simple and economical lever device renders it impossible to open the valve 40 during the resetting operation or at any time that the magnet is not energized and holding the armature in attracted position. Thus, main burner fuel cannot be admitted to the burner compartment before the pilot burner is lighted. There is no danger of explosion when a lighted match is inserted in this compartment for the purpose of igniting the pilot burner.

When the push-button 98 is released after the resetting operation is completed as described, the extension stem 62 and the lever arm 140 are held in the downward position by the reset magnet 56. The coil spring 148, however, rotates the lever arm 138 counter-clockwise about its pivot 144 and causes the valve 40 to be disengaged from its seat against the bias of the spring 42.

It is apparent that if the push rod 124 is being forced downwardly by the clock actuator during the resetting operation, then the collar 112 on the thrust button 72 will be unable to engage the bearing surface 152 on lever arm 138 until the downward movement of the thrust button is nearly completed. Similarly, the coil spring 148 can bias the lever arm 138 only up to the point when the lever arm is stopped by the push rod 124. The remainder of the movement will occur when the clock actuator releases pressure on the push rod 124 causing retraction of this member.

From the foregoing description of the improved control device, it becomes apparent that primary and secondary means may be employed for operating a valve or other control means. Thus, the primary means may be the thermomagnetic unit and the secondary means a clock timer as preferred herein. While it is desirable for the valve to be under safety control of the thermomagnetic unit at all times, it is apparent that the clock timer could be additional equipment to be installed when desired. Provision has been made for the addition of the clock control whenever desired and for its removal for repair without interruption of range operation under full safety control.

It is understood that many changes may be made in the combination and arrangement of parts and in the details of construction within the scope of the appended claims without departing from the spirit of the invention.

I claim:

1. In a control device, control means movable between open and closed positions and biased to said closed position, a first pivotally mounted lever, a second lever pivotally mounted on said first lever and being engageable with said control means, actuating means cooperable with said second lever for moving said second lever into

operative relation with said control means and overcoming the bias of said control means and causing movement of said control means to open position, positioning means operatively engageable with said first lever for positioning said second lever to render said actuating means effective or ineffective to overcome said bias according to the presence or absence respectively of a controlling condition, and means for rotating said second lever on said first lever to move said second lever out of operative relation with said control means to thereby render said actuating means ineffective to overcome said bias during the presence of said condition.

2. In a control device, control means movable between open and closed positions and biased to said closed position, a first pivotally mounted lever, a second lever pivotally mounted on said first lever and being engageable with said control means, yieldable means cooperable with said second lever for overcoming the bias of said control means and causing movement of said control means to open position when said second lever is in operative engagement with said control means, electromagnetic means operatively engageable with said first lever for positioning said second lever to render said yieldable means effective or ineffective to overcome said bias according to the energized or deenergized condition of said electromagnetic means, means for establishing an engaged relation between said first lever and said electromagnetic means including a movable element slidable relative to said electromagnetic means and being engageable with both said levers to move said first lever into engagement with said electromagnetic means while retaining said second lever out of operative relation with said control means and said yieldable means inoperable for overcoming the bias of said control means, said first lever being retained in engagement with said electromagnetic means while said second lever is rotated in one direction by said yieldable means if said electromagnetic means is energized when said movable element is released, and means for rotating said second lever in the opposite direction on said first lever to cause said control means to be closed under its bias in the energized condition of said electromagnetic means.

3. In a control device, the combination of control means movable between controlling positions and being biased to one of said positions, a lever device positioned to be operatively engageable with said control means, yieldable means cooperable with said lever device for positioning the same in operative relation with said control means for overcoming the bias of said control means and causing movement thereof to another of said positions, positioning means operatively engageable with said lever device for positioning said lever device to render said yieldable means operable for overcoming the bias of said control means only during the existence of a controlling condition and inoperable for overcoming said bias in the absence of said condition, and means operable on said lever device for overcoming said yieldable means and causing movement of said control means under said bias to said one position.

4. In a control device, the combination of control means movable between controlling positions and being biased to one of said positions, a lever device adapted to be positioned for operative engagement with said control means, yieldable means cooperable with said lever device for over-

coming the bias of said control means and causing movement thereof to another of said positions when said lever device is positioned in operative engagement with said control means, holding means cooperable with said lever device having a first position during the existence of a controlling condition in which the lever device is positioned in operative engagement with the control device and a second position in the absence of said condition in which the lever device is positioned out of operative engagement with said control device, means operable on said lever device for overcoming said yieldable means and causing movement of said control means under said bias to said one position, and means for setting said holding means in said first position upon establishment of said condition while rendering said lever device and said yieldable means inoperable for overcoming the bias of said control means.

5. In a control device, the combination of control means movable between controlling positions and being biased to one of said positions, a lever device having relatively fixed and movable pivots and adapted to be positioned for operative engagement with said control means, said lever device being so constructed and arranged that rotation thereof on said fixed pivot will cause movement of said movable pivot, yieldable means adapted to rotate said lever device in one direction on said movable pivot for overcoming the bias of said control means when said movable pivot is in a first position and said lever device is in operative engagement with said control means, means operable on said lever device for overcoming said yieldable means and causing rotation of said lever device in another direction on said movable pivot and movement of said control means under said bias, holding means operatively associated with said lever device for retaining said movable pivot in said first position during the existence of a controlling condition, means for rotating said lever device on said fixed pivot and causing movement of said movable pivot to a second position in the absence of said condition, said lever device and said yieldable means being inoperable for overcoming the bias of said control means when said movable pivot is in said second position, and setting means for establishing an operative relation between said lever device and said holding means while retaining said lever device and said yieldable means inoperable for overcoming the bias of said control means, said setting means including a movable element operatively engageable with said lever device for rotating the same on said fixed pivot and causing movement of said movable pivot to said first position.

6. In a control device, the combination of control means movable between controlling positions and being biased to one of said positions, a lever device comprising a pair of lever arms, one of said lever arms having a relatively fixed pivot and the other of said lever arms being adapted for operative engagement with said control means and having a pivot movable with said one lever arm, yieldable means adapted to rotate said other lever arm in one direction on said movable pivot for establishing an operative relation between said other lever arm and said control means and overcoming the bias of said control means while said movable pivot is in a first position, holding means operatively engageable with said one arm for retaining said movable pivot in said first position during the existence of a controlling condition, means operatively engageable with said

other arm for overcoming said yieldable means and causing rotation of said other lever arm in another direction on said movable pivot and movement of said control means under said bias,

5 and means for rotating said one arm on said fixed pivot and causing movement of said movable pivot to a second position in the absence of said condition, said other arm and yieldable means being inoperable for overcoming the bias of said control means while said movable pivot is in said second position.

7. In a control device, the combination of control means movable between controlling positions and being biased to one of said positions, a lever device comprising a pair of lever arms, one of said lever arms having a relatively fixed pivot and the other of said lever arms having a pivot movable with said one lever arm and adapted for operative engagement with said control means, yieldable means adapted to rotate said other lever arm in one direction on said movable pivot into operative engagement with said control means for overcoming the bias of said control means while said movable pivot is in a first position, holding means operatively engageable with said one arm for retaining said movable pivot in said first position during the existence of a controlling condition, means operatively engageable with said other arm for overcoming said yieldable means and causing rotation of said other lever arm in another direction on said movable pivot and movement of said control means under said bias, means for rotating said one arm on said fixed pivot and causing movement of said movable pivot to a second position in the absence of said condition, said other arm and yieldable means being out of operative relation with said control means and being thereby inoperable for overcoming the bias of said control means when said movable pivot is in said second position, and setting means for establishing an operative relation between said lever device and said holding means while retaining said other lever arm and yieldable means inoperable for overcoming the bias of said control means, said setting means including a movable element operatively engageable with both said lever arms for rotating said other lever arm in said other direction on said movable pivot and for rotating said one lever arm on said fixed pivot and causing movement of said movable pivot to said first position.

8. In a control device, the combination of control means movable between controlling positions and being biased to one of said positions, a lever device comprising a pair of lever arms, one of said lever arms having a relatively fixed pivot at one end thereof and the other of said lever arms having a pivot intermediate its ends and being adapted for operative engagement at one end with said control means, said last named pivot being carried by said one lever arm and movable therewith upon rotation of said one lever arm on said fixed pivot, yieldable means engaging the opposite end of said other lever arm for rotating the same in one direction on said movable pivot into operative engagement with said control means for overcoming the bias of said movable means while said movable pivot is in a first position, holding means operatively engageable with the opposite end of said one lever arm for retaining said movable pivot in said first position during the existence of a controlling condition, means operatively engageable with said other lever arm between said movable pivot and said yieldable means for overcoming

the latter and causing rotation of said other lever arm in another direction on said movable pivot and movement of said control means under said bias, means for rotating said one lever arm on said fixed pivot and causing movement of said movable pivot to a second position in the absence of said condition, said other lever arm and yieldable means being out of operative engagement with said control means and being thereby inoperable for overcoming the bias of said control means while said movable pivot is in said second position, and setting means for establishing an operative relation between said lever device and said holding means while retaining said other lever arm and yieldable means inoperable for overcoming the bias of said control means, said setting means including a movable element operatively engageable with both said lever arms for rotating said other lever arm in said other direction on said movable pivot and for rotating said one lever arm on said fixed pivot and causing movement of said movable pivot to said first position.

9. In a control device, the combination of a casing, control means in said casing movable between controlling positions and biased to one of said positions, a lever device adapted to be positioned for operative engagement with said control means, yieldable means cooperable with said lever device for overcoming the bias of said control means and causing movement thereof to another of said positions while said lever device is positioned for operative engagement with said control means, means visible exteriorly of said casing for indicating the position of said lever device, means for operating said indicating means from said lever device, and means for positioning said lever device in operative relation with said control means to render said lever device and said yieldable means operable for overcoming the bias of said control means during the existence of a controlling condition and for position-

ing said lever device out of operative relation with said control means to render said lever device inoperable for overcoming said bias in the absence of said condition.

- 5 10 In a control device, the combination of a casing, control means in said casing movable between controlling positions and being biased to one of said positions, a lever device adapted to be positioned for operative engagement with said control means, yieldable means cooperable with said lever device for overcoming the bias of said control means and causing movement thereof to another of said positions when said lever device is in operative engagement with said control means, means visible exteriorly of said casing for indicating the position of said lever device, actuating means movable with said lever device and projecting exteriorly of said casing, connecting means extending between said indicating means and said actuating means, and means for positioning said lever device in operative relation with said control means to render said lever device and said yieldable means operable for overcoming the bias of said control means during the existence of a controlling condition and for positioning said lever device out of operative relation with said control means to render said lever device inoperable for overcoming said bias in the absence of said condition
